DESIGN FOR A PINEAPPLE SLICE

Helen Hughes Richards, Honolulu, Territory of Hawaii, assignor to Hawaiian Pineapple Company, Limited, Honolulu, Territory of Hawaii, a corporation of Hawaii

Application October 22, 1938, Serial No. 80,631

Term of patent 14 years

To all whom it may concern:

Be it known that I, Helen Hughes Richards, a citizen of the United States, residing at Honolulu, in the Territory of Hawaii, have invented a new, original, and ornamental Design for a Pineapple Slice, of which the following is a specification, reference being had to the accompanying drawing, forming part thereof.

In the drawing, Fig. 1 is a plan view and Fig. 2 an edge view of a pineapple slice, showing my new design.

I claim:

The ornamental design for a pineapple slice, as shown.

HELEN HUGHES RICHARDS.
